UNITED STATES PATENT OFFICE.

HARRY C. MOORE, OF DAYTON, OHIO, ASSIGNOR TO THE AUTOMOTIVE MANUFACTURING COMPANY, OF DAYTON, OHIO, A CORPORATION OF OHIO.

DESIGN FOR A COMBINATION GREASE CUP AND GUN.

60,361.

Specification for Design.

Patented Feb. 7, 1922.

Application filed January 20, 1921. Serial No. 438,750. Term of patent 7 years.

To all whom it may concern:

Be it known that I, HARRY C. MOORE, a citizen of the United States, residing at Dayton, in the county of Montgomery, and State of Ohio, have invented a new, original, and ornamental Design for a Combination Grease Cup and Gun, of which the following is a specification, reference being had to the accompanying drawing, forming part hereof.

The figure in the drawing is a perspective view of a combination grease cup and gun, showing my new design.

I claim:

The ornamental design for a combination grease cup and gun, as shown.

HARRY C. MOORE.

Witness:

HOWARD S. SMITH.
